CLAPPING TOY

Joseph Nigbor, Mount Clemens, Mich.

Application June 18, 1935, Serial No. 27,265

3 Claims. (Cl. 46—99)

This invention relates to toys and more particularly to a toy adapted to be pulled over a plane surface for the purpose of making a noise.

An object of this invention is to provide a toy of this character which may be used by very small children as an amusement and which embodies relatively few parts so that it will not get out of order and may be cheaply manufactured.

Another object of this invention is to provide a device of this character which may have associated therewith a figure which is adapted to be moved up and down and rocked forwardly and rearwardly as the device is pulled over a plane surface.

The above and various other objects and advantages of this invention will in part be described in, and in part be understood from the following detail description of the present preferred embodiment, the same being illustrated in the accompanying drawing, wherein:—

Figure 1 is a longitudinal section partly in detail taken substantially through the center of a device constructed according to an embodiment of this invention;

Figure 2 is a transverse section taken substantially through the center of the device.

Referring to the drawing wherein like numerals of reference designate corresponding parts throughout the several views, the numeral 10 designates generally a hollow body or box which is preferably open at the bottom and the numeral 11 designates a shaft which is rotatably mounted in the box near the open bottom thereof. The shaft 11 has a pair of wheels 12 secured one to each end thereof and the wheels 12 are fixed against rotation relative to the shaft 11 by means of pins 13 or the like. A draw bar or handle 14 is secured to one end of the body 10 and may be of suitable length so that a child may pull the device over a plane surface.

A vertically movable member 15 in the form of a plate or the like is loosely disposed within the housing or box 10 and the box 10 adjacent the lower portion thereof is provided with a plurality of inwardly extending rods or pins 16 which prevent the plate or movable member 15 from dropping out of the open bottom of the box.

The shaft 11 has secured thereto a clapper or operating member 17 which is secured to the shaft 11 within the box 10 and this clapper 17 is adapted to strike the movable member 15 as the shaft 11 is rotated. In this manner the movable member 15 is forced upwardly in the box 10 and the member 15 will fall by gravity so that there will be a constant up and down movement of the mem-

ber 15 as the housing 10 is pulled over a plane surface.

The box 10 is provided with a top 18 having an elongated slot or opening 19 therethrough and a stem or standard 20 is secured at one end to the movable member 15 and is adapted to project loosely through the slot 19. The stem or standard 20 has a narrow slit 21 extending downwardly from the upper end thereof and a figure 22 of suitable configuration is adapted to be mounted in this slit 21 so that the figure 22 will move up and down and back and forth as the standard 20 moves up and down and back and forth with the movement of the member 15. It is to be noted that the opening 19 in the top 18 of the box 10 is of such an extent as to leave a substantial portion of the top to serve as a clapboard in connection with the plate 15 as it is impelled upward by the rotatable clapper 17, and it is also to be noted that in the assembled relation of the parts the plate 15 and its stem 20 surmounted by the figure 22, are entirely loose and unsupported within the box 10 save by the clapper 17, and that the opening 19 is larger both in length and width than the thickness of the stem 20 whereby the plate 15 and stem are not only permitted to have a free up and down movement but a rocking movement in all directions.

In the use of this device the handle or draw bar 14 is grasped by the child and the body or box 10 pulled over the plane surface with the wheels 12 engaging the plane surface. As the box 10 moves forwardly the clapper 17 will raise the movable member 15 in the box 10 and the speed of the box 10 will effect a rapid movement of the member 15 so that this member 15 will also strike the under surface of the top 18 to produce the desired "clapping" sound. As the member 15 moves up and down in the box 10 the figure 22 will also move up and down in addition to moving forward and backward as the member 15 is rocked and raised by means of the operating member 17.

I claim:—

1. A sounding toy of the character set forth comprising a box provided with an open bottom, a wheel supported shaft, a clapper mounted on and carried by said shaft, the box being provided with a top extending thereacross and having an opening therein, a plate mounted in the box above the clapper and adapted to be engaged by the latter in the rotation of the shaft whereby the rapid rotation of the shaft and clapper will impel the plate upward against the lower side of the top of the box to produce a "clapping" sound, and a stem carried by and extending upward

from the plate and accommodated by the opening in the top of the box.

2. A sounding toy of the character described, comprising a box, a wheel supported shaft journaled in the box, a clapper carried by the shaft, a plate freely movable within the box above the clapper and adapted to be engaged by the latter, the top of the box above the plate having an opening formed therein, a stem secured to the plate and extending upward thru said opening, the opening being longer and wider than the stem whereby the stem and the plate may have both a free rocking and up and down movement in the box, and a figure surmounting the stem above the top of the box.

3. A sounding toy of the character described, comprising a resonating box provided with an

open bottom and with inwardly extending pins above the bottom, a wheel supported shaft journaled in the box near the open bottom thereof, a clapper secured to and carried by the shaft between said pins, a plate mounted freely in the box above the clapper and adapted to be struck by the clapper in rapid rotation of the latter whereby it will be impelled towards and in contact with the underside of the top of the box, said top having an opening formed therein, a stem extending up through said opening from the plate to which the lower end of the stem is secured, said opening in the top being longer and wider than the diameter of the stem, and a figure carried by the stem above the top of the box.

JOSEPH NIGBOR.
